SPECTACLE FRONT

Raymond F. E. Stegeman, Greece, N. Y.

Application November 30, 1954, Serial No. 33,331

Term of patent 14 years

(Cl. D57—1)

FIG. 1

FIG. 2

Fig. 1 is a front elevational view of a spectacle front, showing my new design.

Fig. 2 is a top plan view thereof.

Fig. 3 is a front end perspective view thereof.

The essential features of my design are shown in full lines on the drawing.

I claim:

The ornamental design for a spectacle front, substantially as shown and described.
